UNITED STATES PATENT OFFICE.

MONT E. OVERSTREET, OF OKLAHOMA CITY, OKLAHOMA.

BODY LIFTER.

Application filed November 6, 1924. Serial No. 748,243.

The primary object of this invention is to provide a body lifter, by means of which a human body or the like, in a recumbent position, may be lifted and carried from one place to another, without the necessity of an attendant having to touch the body.

The present application is a continuation in part of my application Serial No. 698,460, filed March 11, 1924.

With this and other equally important objects in view, as will be hereinafter more fully pointed out, reference will be had to the accompanying drawing forming a part of this specification and wherein like numerals of reference designate corresponding parts throughout the several views, in which:—

Fig. 1 is a top plan view of one form of the invention, with a body outlined with dotted lines,

Fig. 2 is a top plan view of a second form, with the positions to which the side bars move shown in dotted lines,

Fig. 3 is a view similar to Fig. 2, with one of the connecting straps moved up to the straight portions of the side bars,

Fig. 4 is a diagrammatical cross sectional view of the device with a full line showing of the invention relative to a body covered with a sheet prior to being lifted, and a dotted line showing of the same in lifted and carrying positions,

Fig. 5 is a view in side elevation of the offset handle end of one of the bars,

Fig. 6 is a transverse sectional view taken on line 6—6 of Fig. 3, and

Fig. 7 is a transverse sectional view taken on line 7—7 of Fig. 2.

Referring to the drawings, reference numerals 2 and 3 designate bars or the like of metal tubing or of solid wood, which are placed a distance apart and connected with the bars closer together at their foot ends by means of flexible straps 5 and 6, grip handles 4 being provided at the ends of the bars and being formed preferably of a yielding material such as rubber and with the surface conforming to the contour of the hands.

The strap 5 is formed with a loop 7 at one of its ends and this slidably receives the foot end of the bar 2, and at its opposite end, the strap 5 has a hook 8, which engages around the foot end of the other bar 3 in a detachable and sliding manner. The strap 6 is similarly provided with a loop 7 and

hook 8, but the loop is around the head end of the bar 3 and the hook engages the head end of the bar 2. The object in having the hooks oppositely disposed, is to avoid the necessity of having to slide the straps along the bars when inserting the appliance into a carrying bag. By unhooking the hooks from the bars and turning the bars end for end upon each other, the straps will be coincident and the ends of the bars not having the straps 5 or 6 may then be inserted into the narrow pocket of a carrying bag, not shown. If both straps were carried by the same bar, then one of the straps would have to be moved adjacent the other before the bars could be inserted into the pocket of the carrying bag.

The bars 2 and 3 are spaced apart a distance less than the width of a body to be lifted so that the bars will come back of the outside of the hip bones and back of and outside of the shoulder blades, and the convergence of the bars takes care of the difference in width of the human body at these points. The body lifted rests almost entirely upon the two side bars, and were it not for the necessity of having to support the feet and head, the body would not rest at all upon the connecting straps 5 and 6, and the latter would only function to hold the bars in proper spaced relation.

While in most cases, the arms of the body would not become displaced while the body is being lifted and carried, it is desirable in certain instances to extend a central strap 9 from bar to bar and across the middle section of the body and over the arms. This strap 9 may be attached, preferably detachably, to the side bars 2 and 3 by means of hooks 10, similar to those 8 aforementioned. If desired, the strap 9 may be an exact duplicate of the other straps, including the means of attachment. As a substitute for the strap 9, a sheet 12 or the like which is thrown over the body may be employed in a manner to be hereinafter pointed out.

The form illustrated in Fig. 1 has straight bars 2 and 3 throughout, but the form illustrated in the other views has the ends of the bars 2 and 3 offset at 14, not only to raise the handle grips sufficiently above the surface upon which the body may be resting, but for more important reasons, principally to cause an automatic gripping action of the bars upon the body. This gripping action will be fully described after

the action of the first, or Fig. 1 form, has been recited.

In service, each bar is placed alongside a recumbent body, and its strap 5 or 6 inserted beneath the feet or head respectively of the body and its hook engaged with the other of said bars, previous to which, at least one of the straps was moved along its bar so as to regulate the spacing of that end of the bars when connected according to the width of the body to be lifted. It will be here mentioned that since the width of the skeleton of man varies in about the same proportion to the variations in height, this bringing toward each other of the straps to bring the bars closer together will not take the straps out of a position to support the feet and head of the body. In certain cases, both straps would have to be adjusted, but usually the adjustment of one is sufficient.

Regardless of the amount of flesh on a body, its skeleton or bone frame will be found to be about the same in all men of a given height, and as the bars fit beside the hip bones and shoulder blades, the gripping action is principally upon these parts of the body and upon the flesh between the bars, and it is immaterial how much flesh extends above or beyond the side bars 2 and 3. The device, with a body, is lifted by an attendant at each end grasping the handles 4, and as the weight of the body comes upon the bars, the skeleton and a certain amount of the flesh of the body wedges downwardly between the bars, so that in addition to the weight of the body being upon the bars, there is a certain amount of pinching of the body by the bars, due, not only to the said wedging action, but to an extent to the natural resiliency of the bars themselves. If this pinching action is desired to be increased, the head section may be raised first, whereupon the body will tend to slide a slight amount toward the foot or unraised end, thereby becoming wedged more completely between the converging bars. By employing the strap 9, the arms may be confined in certain cases, though usually the body is gripped in such a firm manner that it can be handled perfectly without the arms becoming disturbed or requiring to be confined. In place of the strap 9, a sheet 12 may be placed over the body, the bars placed alongside the body and upon the sheet, the straps 5 and 6 connected to the bars, and when the body is lifted, the sheet will be pinched between the bars and the body and the arms of the body perfectly confined.

With the form of the invention which employs the bent or offset handles, the bars are applied to the sides of a body and connected by the straps 5 and 6, in the same manner as before, and the bars 2 and 3 in the positions A—A of the diagram in Fig. 4, which is the full line position of Fig. 2.

As the weight of the body comes upon the bars, they turn in the hands of the attendants, from the A—A position to the B—B position of Fig. 4, which is the dotted line position in Fig. 2. Thus, since the spacing of the bars 2 and 3 in the said A—A position is greater than that in the B—B position of the same view, this moving together of the bars automatically under the weight of the lifted body will cause an increased and positive pinching action upon the body, and particularly upon the confined flesh and hip and shoulder bones. The strap 9 may be used with this form, the same as with the other form, as may also the sheet 12, but here the twisting movement of the bars 2 and 3 causes a tightening of the strap or sheet upon the upper part of the body and its arms, binding the same more securely to the carrying bars.

The spacing of the bars is regulated by sliding one or both of the straps 5 and 6 along the bars. Whether one or both is moved, the convergence of the bars changes. With the bent or offset form, when only one strap is moved up to the straight part of the bars, as in Fig. 3, the pinching action is present as before, but it is greatest at the opposite end, and since it is usually the foot end strap that is adjusted, the pinching will be upon the hip and shoulder bones as before.

It is not feasible to recite here all the uses and advantages of this invention, but some of the more important ones will be stated. In attending the sick or the dead, with appliances now on the market, it often becomes necessary for the attendant to insert his hands and arms beneath the body, and where dangerously contagious sores are present on the back of the body, unknown to the attendant, contraction of the disease by the attendant is often the case. This contact with the body by the attendant becomes unnecessary with the present invention since the head and foot straps can be inserted beneath the neck and ankles without the flesh of the attendant's hands having to touch that of the body. With other appliances, if the body is not lifted by being grasped by the hands of the attendant, as stated, then it is often rolled onto a stretcher, causing a flexing of the body which flexing may cause pain to a patient, or purging of a dead body. The latter is explained by the fact that because of the accumulated gas within the intestines and other pockets of the body, any flexing of the body of the corpse will cause this gas to expel the fluid and other contents through the various body openings and often onto the apparel of the corpse or of the attendant, with the incident danger of contagion by the latter. After the body is upon the bars, of this invention, the wedging and gripping action

holds it immovably, so that there is no danger of this undesirable flexing of the body, and further, the body may be placed considerably toward the vertical and carried or held in that position without danger of becoming displaced. Where a body already covered with a sheet is to be lifted and carried, the covering need not be disturbed in order to lift the body with the present invention, nor while in use will the sheet or other body covering become displaced to expose the body. When a hysterical patient is to be moved, his arms may be confined by use of the strap 9 or the sheet 12, and even when neither is employed, because of his inability to effectively grasp the side bars, he is unable to raise himself to an unmanageable extent.

What is claimed:

- 20 1. A body lifter comprising a pair of bars of a length substantially equal to the length of a full grown average human being, and adapted to be placed alongside of a recumbent body so that the body will rest on said bars, handles arranged at the ends of said bars, and spaced cross straps connecting said bars, the space defined by said bars and said straps being constantly open to permit the body to readily sink downwardly against the bars when the latter are lifted.
- 25 2. A body lifter comprising a pair of bars of a length substantially equal to the length of a full grown average human being, and adapted to be placed alongside of a recumbent body so that the body will rest on said bars, handles arranged at the ends of said bars, and spaced cross straps connecting said bars, the space defined by said bars and said straps being constantly open to permit the body to readily sink downwardly against the bars when the latter are lifted, said straps being freely movable along said bars toward and away from each other to provide transverse supports for bodies of various lengths.
- 30
- 35
- 40
- 45

3. A body lifter comprising a pair of bars of a length substantially equal to the length of a full grown average human being, and adapted to be placed alongside of a recumbent body so that the body will rest on said bars, handles arranged at the ends of said bars, and spaced cross straps connecting said bars, the space defined by said bars and said straps being constantly open to permit the body to readily sink downwardly against the bars when the latter are lifted, each strap having one of its ends detachably connected to one of the bars whereby either strap may be threaded beneath the body and be attached to the bar which it detachably engages without the operator touching said body.

4. A body lifter comprising a pair of converging bars of a length substantially equal to the length of a full grown average human being, and adapted to be placed alongside of a recumbent body so that the body will rest on said bars, handles arranged at the ends of said bars, and spaced cross straps connecting said bars, the space defined by said bars and said straps being constantly open to permit the body to readily sink downwardly against the bars when the latter are lifted.

5. A body lifter comprising a pair of bars of a length substantially equal to the length of a full grown average human being, and adapted to be placed alongside of a recumbent body so that the body will rest on said bars, handles arranged at the ends of said bars, and spaced cross straps connecting said bars, the space defined by said bars and said straps being constantly open to permit the body to readily sink downwardly against the bars when the latter are lifted, each of said bars having a straight intermediate portion and offset end portions.

In testimony whereof I affix my signature.
